RETORE

Frederick Pope, Wilton, Conn., assignor to
American Cyanamid Company, New York,
N. Y., a corporation of Maine

Application September 3, 1938, Serial No. 228,282

5 Claims. (Cl. 202—104)

The present invention relates to a retort useful for many purposes but particularly adapted for the heat treatment of wood, coal and the like and from which distillation or destructive distillation products may be recovered.

The principal object of the invention is the provision of mechanism which may be readily manufactured and assembled into a retort capable of withstanding the temperatures to which it 10 may be normally subjected with minimum warpage and destruction, which will have high capacity for material to be treated and products to be recovered therefrom.

To this end, the invention contemplates a series of heating elements adapted to be superimposed one on the other to a vertical stack around a central stationary supporting column, which may be hollow, so as to form a continuous, circuitous heating flue. Each of the heating elements 20 is provided with a substantially horizontal heating surface adapted to receive the wood or other material to be heat treated. Conveyors are provided for carrying the material to be treated around the annular heating surfaces and to drop 25 such material through an aperture provided in each heating element onto the element beneath it and so on seriatim downwardly through the stack of heating elements.

The conveyors are moved by reason of a framework to which they are attached, the framework 30 including a centrally located gear operating from the periphery thereof. The retort is provided with a stationary outer casing, with water seals between this stationary part of the mechanism and the rotating gear assembly. Means to supply products of combustion are provided so that the hot gases therefrom pass upwardly through the stack of hollow heating elements and are discharged from the top thereof into a waste heat boiler if desired. A separate take-off for products 40 of combustion may be supplied to furnish heat to a waste heat boiler where this is found to be advantageous.

A plurality of take-offs for distillation products 45 are connected into the space between the outside of the heating elements and the inside of the stationary casing and such products may then be passed to a suitable recovery and/or purification system as desired. By locating take-offs at 50 different vertical points of the retort, the character of distillation products recovered may be varied. Means are also provided for supplying the material to be heat treated to the horizontal surface of the uppermost heating element for moving it peripherally thereof and for discharg- 55

ing the spent material after it has been removed from the lowermost heating element. Where desired, this spent material may be used to generate combustion gases for supplying heat to the retort.

The invention further consists in the novel arrangement, combination and construction of parts more fully hereinafter described and shown in the drawings, in which:

Fig. 1 is an elevation generally showing the 10 assembly;

Fig. 2 is a fragmentary sectional elevation of the retort of Fig. 1 showing the details of construction and assembly;

Fig. 3 is a sectional plan along the line 3—3 15 of Fig. 2;

Fig. 4 is an elevation of the retort showing the outside stationary casing in dot and dash lines and illustrating the manner of feeding the heating medium to the heating elements, for moving 20 the conveyors and for taking off the distillation products;

Fig. 5 is a bottom plan view of one of the heating elements;

Fig. 6 is a half sectional-half elevational view 25 along the line 6—6 of Fig. 5 and showing the details of the heating element construction;

Fig. 7 is a detail sectional view along the line 7—7 of Fig. 6;

Fig. 8 is a fragmentary plan view along the 30 line 8—8 of Fig. 4;

Fig. 9 is a partial perspective of the upper part of the frame assembly.

Referring now to the particular embodiment illustrated in Fig. 1, an outer stationary casing 35 is shown to consist of the two parts 1 and 2, the latter being suitably mounted upon a base 3 and the former being carried by any suitable overhead support not shown. The lower part of the upper casing section 1 dips into a water or other liquid seal 4 (Fig. 4), while a similar seal 5 is carried by the upper portion of the lower section 2 of the outer casing into which dips a cylindrical section 6 depending from a framework 7. This framework will be more fully hereinafter described with relation to other functions, it being necessary only to mention it at this time in order to make clear that the outer casing is stationary 40 and forms the body of the retort proper.

On the base 3 (Fig. 4) is located a platform 8 50 carrying a supporting column 9 either hollow or not, as desired. On an upwardly extending portion of the platform 8 is located an annular plate 10 carrying the lowermost heating element and serving as a support for those heating ele- 55

ments above it. This plate is provided with a central annulus 11 through which the products of combustion used for heating pass on their way to the upper heating elements. An aperture 12 near the periphery of the plate is located immediately over one end of the discharge screw 13 used for removing the spent material from the retort.

Each of the individual heating elements arranged above the annular plate 10 is of a similar construction and comprises two substantially hemispherical hollow sections 14 and 15, (Figs. 5 and 6), the latter having an aperture 16 therein, bolted together as shown in Fig. 7, the element as a whole being generally of inverted frusto-conical formation. Each element, therefore, has a substantially horizontal upper heating surface 17 and a deflecting lower portion 18 which serves to deflect the products distilled from the material undergoing treatment to the space between the periphery of the heating elements and the outside stationary chamber. Near the inner annulus of the heating surface 17 of each heating element is a peripheral rib 19 (Fig. 2) adapted to receive, between it and the inner wall of the heating element annulus, the lowermost edge of the deflecting portion 18 of the heating element immediately above. In this way, each heating element serves as a support for the heating element above it.

Beneath the heating surface 17 of each heating element is a series of depending fins 20 curved as shown in Fig. 5. These fins serve the dual purpose of first assisting heat transfer from the combustion gases going through the heating elements to the heating surface 17 and, second, due to their curvature, they tend to create a swirling motion of the heating gases and, consequently, prolong their contact with the heating elements. In this way, maximum heat transfer efficiency is obtained.

Also surrounding the supporting column 9 is a series of clay or firebrick deflectors 21 (Fig. 2) of an annular nature, the outer periphery of which extends between the portions 17 and 18 of each of the heating elements. These serve to direct the heat away from the column and into the heating elements. By arranging the lower surface of the deflectors 21 in the form of a substantially inverted frusto-conical configuration which merges into a cylindrical portion, they more or less conform to the somewhat similar shape of the portions 18 of the heating elements. Consequently, a generally uniform passageway for the heating medium is provided. As indicated, each of the upper deflectors 21 rest upon the top of the one immediately beneath it while the lowermost deflector rests upon the top of a cylindrical member 22 (Fig. 4) of the some common position so as to protect the column from the deleterious effects of heat.

Operating on the horizontal surface 17 of each heat element is a conveyor for moving the material to be treated over the heating surface. This is shown in Fig. 3 to consist of an inner hub portion 23 with an outer rim 24 with curved scrapers 25 extending therebetween. The height of these last three elements will depend upon the character of the material undergoing heat treatment. It is contemplated, however, that the compartments defined by the space between the hub, outer rim and two adjacent curved scrapers will be maintained substantially full of the material undergoing treatment. As shown in Fig. 2, the inner hub 23 is arranged to lie outside of

the annular rib 19 on the heating element surface 17. Consequently, the conveyors are guided thereby in their travel around the heating surface and this insures the maintenance of their concentricity.

As shown in Fig. 3, pairs of outwardly projecting fingers 26 are provided on the outside of the outer rim 24 to engage T-irons 27 which extend vertically within the retort. The T-irons are connected at the top and bottom with L-members 28 (Fig. 4). The entire structure comprising the T-irons 27 and the L-members at the top and bottom thereof is carried by the framework 7 by means of upwardly and downwardly projecting arms 29 secured to the T's in any suitable manner.

The framework 7 also carries a master gear 30 (Figs. 1 and 2) which extends between the upper and lower sections of the outside stationary casings 1 and 2. This gear 30 is supported on rollers 31 mounted on the top of standards 32 anchored in the base 3. It is preferable that three such rollers be provided in order to assure a steady support to the gear. Inasmuch as there is a loose slip connection between the fingers 26 and the T's 27, any unevenness of motion of either the gear or the conveyors will not be transmitted to the other.

The gear 30 is provided with peripheral teeth 33 with which meshes drive worm 34 connected by shaft 35 to a motor or other type of prime mover 36. This same motor is utilized to drive the feed and discharge mechanism for the material undergoing treatment through pinion 37, telescopic shafts 38 and worm gear trains 39, 35 all in synchronism.

In assembling the mechanism so far described and with reference to Fig. 4, the lowermost conveyor is placed over the supporting column 9 to rest on the lower annular heating plate 10, the inner hub 23 lying immediately outside of the annular rib 19. The clay or firebrick cylinder 22 is then placed over the column and the first annular deflector 21 similarly moved into position to rest on the top of the part 22. Two halves of the lowermost heating element are now assembled around the column and bolted together, dowel pins 40 (Fig. 7) fitting into strengthening flanges 41 on the heating elements assisting in maintaining parts in proper alignment. It is important at this point to arrange the aperture 16 in this heating element out of alignment with the aperture 12 (Fig. 3) in the plate 10 in a clockwise direction inasmuch as in the present embodiment, the conveyors are designed to move in a clockwise direction. This is for the reason that it is desired to have the material undergoing treatment on the upper surface of each heating element to travel under impetus of the conveyor, completely around that element, drop through its aperture onto the next element, and so on down the stack of elements.

Locking keys are provided between heating elements in order to maintain them in a stationary position and to prevent relative movement therebetween.

In the same manner, successive conveyors, deflectors and heating elements are assembled until the entire stack of these parts are in their proper position.

As the heating elements are assembled, it is important that the pairs of fingers 26 be made to straddle and engage their respective T-irons 27.

After all of the heating elements have been

put into place, an exhaust stack section 42 (Fig. 4) is fitted within the upstanding peripheral rib 19 of the uppermost section. The exhaust gases are conducted away and disposed of in a manner to be more fully hereinafter described.

The material to be treated is preferably fed into the still through the hopper 43 (Fig. 1) through a starwheel 44 moved by gear train 39 and onto the top of the first heating element. The spent material discharged from the last heating element drops onto worm 13 (Fig. 4) for disposal or, if desired, to the furnace for supplying heating gases.

Heat is generated for the retort in a furnace 45 using either oil fed through line 46 or other fuel including waste from the retort, as may be found most expedient. The combustion gases from the furnace pass through the neck 47 and into the chamber 48 and from thence through the annulus surrounding the lower part of the supporting column 9 and into the first heating element as in Figs. 1 and 4.

Inasmuch as it may be desirable to utilize steam in purifying the products discharged from the retort, the discharged heating medium still containing some sensible heat, may be passed through a waste heat boiler 49 and from thence back into the circulation system through the downcomer 50. A feed water heater 51 is likewise provided into which the exhaust heating gases may be by-passed by suitable manipulation of the damper 52. On the other hand, if for any reason it is found unnecessary to abstract remaining heat from the exhaust gases, they may be vented to the atmosphere through stack 53. To facilitate recirculation of the exhaust gases, fan 54 is provided.

The operation of the device is as follows:

Combustion gases are generated in furnace 45 and passed through chamber 48 into the first heating element admixed or not with exhaust gases coming from the downcomer 50. It is preferable that the combustion gases entering the first heating element be at a temperature of from 1400 to 1500° F. and for this purpose, dilution with the cooler exhaust gases may be desirable in order to maintain this temperature within the required range. Actually the temperature to be used in the retort will depend upon the character of material undergoing treatment and the character of distillation products desired. In distilling and destructive distilling resinous woods, red wood, coal or the like, it has been found desirable to introduce the heating gases at say from 1400 to 1500° F. and to discharge them at from about 900 to 1000° F.

The material undergoing treatment in a suitable form of subdivision is fed in through the hopper 43 and reaches the top of the uppermost heating element, falling within the confines of the hub 23, outer rim 24 and the curved scrapers 25. The conveyor moves preferably in a clockwise direction and, consequently, moves the finely divided material around the top of the uppermost heating element until it finally drops through the aperture therein onto the next heating element. It is to be noted that due to the fact that the scrapers 25 are curved, they have no difficulty in passing over the joint between the substantially hemispherical sections of the heating elements and, consequently, have no tendency to become temporarily stopped in case the heating elements or the scraper becomes warped from the heat. In a similar manner, the material undergoing treatment moves around each heating element and

drops down through its aperture onto the heating element immediately below.

In case the material undergoing treatment becomes caked or otherwise agglomerated so that there would be a tendency for it to pass over the aperture in any heating element, concentrically curved and downwardly extending blades 55 (Figs. 2, 5 and 6) having inclined bottom edges 56 are provided on the lower section of each heating element immediately above the aperture in the heating element below. Consequently, as the agglomerated cake is pushed around, when it reaches the aperture through which it should pass, the top of it engages the bottom of the depending deflector blades and they force the cake to be broken up and to drop through the aperture onto the heating element beneath.

The volatile natural products or distillation or destructive distillation products from the material undergoing the heat treatment pass upwardly between the outer stationary casing and the heating elements and out of either or both flues 57 and 59 to one or more suitable recovery systems. Obviously the products thus recovered may be further purified or separated as desired.

It has been found desirable in some instances to separately collect products generated in different parts of the retort. In order to make this possible in the present apparatus, an annular plate 58 (Figs. 2 and 4) is provided which rests on continuous flanges on the lower section 2 of the outer casing and the outer edge of one of the heating elements respectively. The upright T-irons 27 pass through corresponding slots in this plate and the latter moves around with the T's and their framework as the master gear rotates. In this way, the retort is effectively separated into two compartments. The products from the lower compartment, that is, that section beneath the plate 58 may be taken off through the port 59 and separately recovered and/or purified. Obviously the plate 58 and port 59 may be located in any desired relative vertical position depending upon the character of products to be recovered and the character of the material undergoing treatment. If there is no desire to separate such products, the port 59 may be suitably connected to the flue 57 and all products collected together.

As above mentioned, the spent waste is discharged through the worm 13 for disposal as desired.

From the above it will be apparent that a retort has been devised which is particularly desirable for the purpose specified. It will, of course, be obvious that inasmuch as retorts of this character are subjected to high temperatures, there is a great tendency toward warpage or even destruction of the parts subjected to the intense heat. Consequently, it is desirable that the outside casing which, perhaps, is of the greatest area of any part in the entire mechanism should be firmly fixed upon its foundation in a stationary manner, for were it permitted to move, it would be difficult to maintain it in proper alignment and relationship with the remaining parts of the equipment. In the present assembly, the initially moving parts are the master gear and those elements immediately connected thereto. These are supported in an entirely satisfactory manner and in a way which will not interfere with the stability or alignment of the outside casing. There being no fixed and immovable connection between the master gear assembly and the conveyor assembly, each part is free to move without caus-

ing distortion of the other and with a minimum amount of friction.

While the invention has been shown and described with particular reference to specific embodiments, it is to be understood that it is not to be limited thereto but it is to be construed broadly and limited only by the scope of the claims.

I claim:

- 10 1. A retort comprising a stationary outside casing, a stack of superimposed hollow heating elements therein, means to supply heat to the interior of the heating elements and to take the exhaust gases therefrom, means to supply material to be heat treated onto the uppermost heating element, conveyor means for moving the said material peripherally on each heating element and to drop the same downwardly onto the next heating element of the stack, said conveyor means 15 having a drive element projecting outwardly beyond the stationary outside casing and between the top and bottom thereof, means to drive said element, means for discharging waste material from the retort and take-off means for the distillation products from the material being heated, 20 in which the take-off means comprises a plurality of ports spaced apart vertically of the retort, with plate means between the take-offs to shunt distillation products below it into the lower take-off, said plate being annular and carried 25 between the stationary outer casing and a heating element and relatively movable thereto.
- 20 2. A retort comprising a stationary outside casing, a stack of superimposed hollow heating elements therein, means to supply heat to the interior of the heating elements and to take the exhaust gases therefrom, means to supply material to be heat treated onto the uppermost heating element, conveyor means for moving the said material peripherally on each heating element 25 and to force the same downwardly onto the next heating element of the stack, said conveyor means having a drive element projecting outwardly beyond the stationary outside casing and between the top and bottom thereof, means to drive said 30 element, means for discharging waste material from the retort and take-off means for the distillation products from the material being heated in which the means for forcing material downwardly comprises ribs depending from the 35 bottom of a heating element, said ribs being of a depth increasing in extent in the direction of travel of the material being treated.
- 30 3. A retort comprising a stationary outside casing, a stack of superimposed hollow heating elements therein, means to supply heat to the interior of the heating elements and to take the exhaust gases therefrom, means to supply material to be heat treated onto the uppermost heating element, conveyor means for moving the said material peripherally on each heating element 40 and to drop the same downwardly onto the next heating element of the stack, said conveyor means having a drive element projecting outwardly beyond the stationary outside casing and between the top and bottom thereof, means to drive said element, means for discharging waste material from the retort and take-off means for the distillation products from the material being heated, 45 in which the take-off means comprises a plurality of ports spaced apart vertically of the retort, with means between the take-offs to shunt distillation products below it into the lower take-off.
- 40 4. A retort comprising a stationary outside casing, a stack of superimposed hollow heating elements therein, means to supply heat to the interior of the heating elements and to take the exhaust gases therefrom, means to supply material to be heat treated onto the uppermost heating element, conveyor means for moving the said material peripherally on each heating element 50 and to drop the same downwardly onto the next heating element of the stack, said conveyor means having a drive element projecting outwardly beyond the stationary outside casing and between the top and bottom thereof, means to drive said element, means for discharging waste material from the retort and take-off means for the distillation products from the material being heated, 55 with refractory deflectors arranged around a central flue, said deflectors projecting into the hollow heating elements whereby heat passing up the flue will be forced by the deflectors radially into the heating elements.
- 50 5. A retort comprising a stationary outside casing, a stack of superimposed hollow heating elements therein, means to supply heat to the interior of the heating elements and to take the exhaust gases therefrom, means to supply material to be heat treated onto the uppermost heating element, conveyor means for moving the said material peripherally on each heating element 60 and to drop the same downwardly onto the next heating element of the stack, said conveyor means having a drive element projecting outwardly beyond the stationary outside casing and between the top and bottom thereof, means to drive said element, means for discharging waste material from the retort and take-off means for the distillation products from the material being heated, with refractory deflectors arranged around a central flue, said deflectors projecting into the hollow heating elements whereby heat passing up the flue will be forced by the deflectors radially into the heating elements.

FREDERICK POPE.
